United States Patent Office.

JAMES AMES, OF INDIANAPOLIS, INDIANA.

Design No. 3,973, dated April 19, 1870.

DESIGN FOR A MASONIC CHART.

The Schedule referred to in these Letters Patent and making part of the same.

To all whom it may concern:

Be it known that I, JAMES AMES, of Indianapolis, in the county of Marion and State of Indiana, have invented a new Design for a Masonic Chart; and I do hereby declare that the following is an exact description thereof, reference being had to the accompanying drawing representing the design.

In the center of the foreground is represented the Temple of Solomon, and builders upon it engaged in its construction, while workmen, beasts of burden, and materials, occupy the ground in front of it.

At the right hand, in the foreground, appears the outer court of the temple.

At the left hand, in the foreground, is shown the second court of the temple, containing Solomon's grand lodge.

In the center of the background are figured the emblems of the order, upon an altar or an escutcheon.

At the right hand, in the near background, is the lodge of sorrow.

Beyond the lodge of sorrow is represented a city in the course of building, near Jerusalem.

Nearer the center appear men taking wood from Lebanon and lading it in vessels for Jerusalem.

At the extreme left hand, in the background, is a cemetery, and angels therein standing by a broken monument.

Nearer the center is a field, and in it a sheaf of wheat.

What I claim as my invention, and desire to secure by Letters Patent, is—

The design for a masonic chart, as herein represented and described.
